UNITED STATES PATENT OFFICE.

JOHN REDMOND, OF NEW YORK, N. Y.

CONDENSATION RECEIVER AND PUMP.

1,411,585.

Specification of Letters Patent. Patented Apr. 4, 1922.

Application filed January 8, 1921. Serial No. 435,883.

To all whom it may concern:

Be it known that I, JOHN REDMOND, a citizen of the United States, and a resident of the city, county, and State of New York, have invented a new and useful Improvement in Condensation Receivers and Pumps, of which the following is a full, clear, and exact description.

My invention relates to improvements in condensation receivers and pumps, and the object of my invention is to produce an exceedingly simple and absolutely automatic structure which will receive and handle water at a higher temperature than ordinary pumps, and deliver it to the boiler or wherever desired regardless of pressure. My invention is intended to produce a fuel saving apparatus which will eliminate piston and centrifugal pumps, pump governors, etc., in many installations, and which is useful as a steam trap or condenser to receive the return steam and water of condensation in buildings and automatically deliver it to the boiler. My invention can also be used as a jet condenser, and to transport oil or other liquid by using compressed air from one point to another. It can also be used for receiving and delivering sewage up to the main sewer in buildings where the lower floors are below the main sewer line. In carrying out my invention, I employ a pair of tanks which alternately receive and discharge water of condensation, or other liquid, and which tilt automatically as they are filled and discharged, and automatically cut off the pressure fluid whether it be air, steam, or the like. The invention will be better understood from the description which follows.

Reference is to be had to the accompanying drawings forming a part of this specification, in which similar reference characters indicate corresponding parts in all the views.

Figure 1 is a side elevation of the apparatus embodying my invention.

Figure 2 is a plan view thereof.

Figure 3 is a detail view partly in section of one of the tanks and some of its connections.

Figure 4 is a broken vertical sectional view showing the port connections at the foot of one of the tanks.

Figure 5 is a detail of one of the valve arrangements for cutting off the pressure fluid from the tanks alternately.

Figure 6 is a modification of the structure shown in Figure 5, and

Figure 7 is a detail of the air relief valve. The apparatus can be mounted in any suitable frame, and I have shown it provided with a base 10 having a central framework 11 and an arched frame work 12, serving to support and guide the tanks and the operating connections. I employ a pair of tanks 13 and 14 which are exactly similar and which have similar connections, so that the description of the connections of one applies equally to the other. Each tank has a relatively large pipe 15 opening from the bottom and vertically arranged, which is provided with intake and discharge ports 16 and 17, adapted to register with the inlet and discharge ports 18 and 19 in the pipe 20, which is vertically arranged on the base 10, and these pipes 20 serve in a manner as dash-pots as well as valve casings. It will be seen that when the tank is in its raised position, the port 16 will register with the port 18, so that the inflow can pass to the raised tank, but the port 17 will be above the port 19, and the latter will be closed by the apron 21. A similar apron 22 balances the pipe 15 and slides in the pipe 20.

It will be seen, therefore, that the port 18 is opened only when its tank is receiving the inflow of water, and the port 19 will be opened only when the tank is depressed and the liquid is being ejected.

These pipes 20 connect by a circulation pipe 23 having a valve 24 by which the rapidity of the circulation can be regulated, and thus by providing the resistance when the tank drops, a dash-pot effect is had without interfering with the operation of the structure. The tanks are pivotally connected on opposite sides to links 25 which are pivoted to walking beams 26, these being pivoted in the supports 11 so that the tanks will rise and fall alternately. They can be guided in any suitable way. The pipe 15 serves in a measure as a guide, and they can be further guided by rods 28 attached to the tops of the tanks and extending through the upper part of the arched frame 12.

To prevent the tanks from tipping too soon they are temporarily locked with one tank in its lower position by the following means. Each tank has near the bottom a bail 29 which extends downward between spring latches 30 adapted to snap over the bail,

and these pass through a keeper 31 supported by an arm 32 or equivalent support, and the tension of the latches can be regulated by the screws 33. Thus they can be 5 adjusted so that when the full tank is down as shown at the left in Figure 1, the latches will engage the bail 29, but as the tank 14 becomes empty and the tank 13 full, the weight of the latter will cause it to drop, 10 thus raising the tank 14 and releasing it from the latches 30.

The pressure fluid is admitted to the tanks from a pipe 34 which can connect with the boiler pressure or with a source of compressed air or other pressure fluid. This pipe connects with a cross pipe 35 which in turn connects with the vertical valve casings 36 in each of which is a piston 37 adapted to close the end of the pipe 35. 15 The pistons 37 connect on the under side by means of rods 38 with links 39 which are pivoted to one of the walking beams 26. Thus when the tanks are in the position shown in Figure 1, it will be seen that the 20 valve casing 36 connecting with the tank 14 will be open to admit pressure fluid to said tank and facilitate the discharge of material therefrom, while the pressure fluid will be shut off from the tank 13, and as 25 the positions of the tanks change, the valves will also change, obviously. One valve casing 36 connects by the pipe 40 with the tank 13, and the other by a pipe 40^a with the tank 14. In detail the pipes 40 and 40^a 30 connect with pipes 41, and these with vertical pipes 42 having a sliding connection with the pipes 43 on the tanks 13 and 14. Each pipe 41 is prolonged and connected with a valve casing 44 in which is a piston 44^a, the piston rod 46 of which pivotally connects with a lever 47 which is pivoted at one end to the tank by means of links 49, and at the other end is pivoted to a support or bracket 48 on the frame 12. 45 Thus when the tank is being filled, the valve 44^a will be open to permit the escape of air, but when the tank is full, it will be closed so that pressure fluid may properly work on the contents of the tank. As an 50 additional safeguard to insure the cutting off of pressure fluid, instead of having the construction shown in Figure 5 for cutting off the pressure fluid, the modification shown in Figure 6 can be used. In this 55 case the pipe 34 connects by a branch pipe 50 with opposite ends of a horizontally arranged cylinder 51 in which slides a piston 42 adapted to alternately open and close the pipes 40 and 40^a, and the piston rod 53 connects by a link 54 with a bell-crank 55 which is pivoted as shown at 56, and can be suitably connected with one of the tanks or arms 39 to operate the valve. As an additional safeguard to make sure that the steam is shut 60 off when a tank is empty, each tank is pro-

vided with a float 57 connected to a rod 58 which is secured to a shaft 59 extending from a suitable stuffing box in the shell of the tank, and the shaft is provided with a crank 60 having a loose connection with a 70 rod 61 suitably mounted, and this pivotally connects by means of a link 62 and arm 63 with a valve 64. This loose connection in the present instance comprises a sliding connection 60^a between the crank 60 and the 75 rod 61, said sliding connection being in the form of a ring which reciprocates between the collars 60^b and 60^c which are spaced apart and fixed to the rod. As the crank 60 swings up or down, the member 60^a will 80 slide correspondingly, having a lost motion between the collars 60^b and 60^c, and the rod 61 swinging on its pivot permits this action. When the ring 60^a strikes either collar, it moves the rod 61 down or up as 85 the case may be, and so actuates the valve 64.

From the foregoing description it will be seen that I have provided a simple and positive structure which works automatically, and can be easily applied to any of 90 the purposes stated. When a tank is full it drops as shown at the left hand in Figure 1, and the empty tank rises, and by the mechanism described pressure fluid is admitted to the full tank so as to force the 95 liquid therefrom, while the pressure fluid is automatically cut off from the empty tank. The water will then flow into the empty tank, the air meanwhile passing out through the relief valve 44, and when the 100 second tank is full, it drops and the action described is repeated. Thus it will be seen that when the apparatus is installed and started, it needs no attention, but does its work as long as liquid and pressure fluid 105 are supplied.

I claim:—

1. An apparatus of the kind described comprising a pair of tanks connected so as to alternately rise and fall, pipes arranged 110 below the tanks and provided with intake and outlet ports, and pipes acting as pistons on the under side of the tanks and entering the first mentioned pipes, the piston pipes having ports therein registering with the 115 aforesaid inlet and outlet ports.

2. An apparatus according to claim 1 characterized by the further fact that a pressure fluid connection is provided for each tank together with automatic means 120 for diverting pressure fluid to the full tank and cutting it off from the empty tank.

3. An apparatus of the kind described comprising a pair of tanks adapted to alternately rise and fall, vertical pipes arranged 125 below the tanks and provided with inlet and outlet ports, piston pipes leading from the bottoms of the tanks and entering the aforesaid vertical pipes, the piston pipes having ports to register with the inlet and 130

outlet ports of the vertical pipes, a circulation pipe connecting said vertical pipes, and means for admitting pressure fluid to each tank as it becomes full.

5 4. An apparatus of the kind described comprising a pair of tanks adapted to alternately rise and fall, vertical pipes arranged below the said tanks and provided with inlet and outlet ports, piston pipes opening 10 from the tank bottoms and entering the vertical pipes, said piston pipes having ports to register with the ports of the vertical pipes, a fluid pressure supply pipe having a connection with each tank, and 15 automatic means for diverting said fluid pressure to the full tank and cutting it off from the empty tank.

5. An apparatus of the kind described comprising a pair of tanks adapted to alternately rise and fall according as they are 20 empty or full, a pressure fluid connection for each tank, a valve mechanism automatically controlled by the rise and fall of the tanks for opening and closing the pressure 25 fluid connection, an air relief pipe opening from the upper part of each tank, a valve controlling said air relief pipe, a pivoted

arm above each tank operatively connected with the aforesaid valve, and a connection between the tank and one end of the arm 30 whereby the rise and fall of the tank operates the arm and valve.

6. The combination with the tanks adapted to rise and fall as described, a pressure fluid supply pipe for the tanks, a valve 35 mechanism controlling the pressure fluid supply to the tanks, mechanism operated by the rise and fall of the tanks to cut the pressure fluid from one tank and open it to the other, and a secondary pressure fluid 40 control for each tank comprising a valve in the pressure fluid line, a float in the tank, and an operative connection between the float and said secondary valve.

7. The combination with a pair of tanks 45 adapted to alternately rise and fall, of bails in the tank bottoms, opposed latches adapted to engage the bails, and means for regulating the tension of the latches.

JOHN REDMOND.
